To all whom it may concern:

Be it known that I, George H. Bingham, Jr., a citizen of the United States of America, residing at Taneytown, county of Carroll, and State of Maryland, have invented a new, original, and ornamental Design for a Boot, of which the following is a specification, reference being had to the accompanying drawing, forming a part thereof.

Figure 1 is a side perspective view of a boot, embodying my new design;

Figure 2 is an opposite side perspective view thereof;

Figure 3 is a side perspective view, similar to Figure 1, with the upper portion of the boot open, and

Figure 4 is a rear perspective view of the boot, as shown in Figure 1.

I claim:

The ornamental design for a boot, as shown.
